DESIGN FOR A BENCH FOR LATHES OR THE LIKE

Henry H. Logan, Chicago, Ill., assignor to Logan
Engineering Co., Chicago, Ill., a corporation of
Illinois

Application March 1, 1943, Serial No. 109,645

Term of patent 14 years

To all whom it may concern:

Be it known that I, Henry H. Logan, a citizen
of the United States, residing at Chicago, in the
county of Cook and State of Illinois, have in-
vented a new, original, and ornamental Design
for a Bench for Lathes or the like, of which the
following is a specification, reference being had
to the accompanying drawing, forming a part
thereof.

Fig. 1 is a front elevation of a bench for lathes
or the like, showing my new design; and

Fig. 2 is a rear perspective view thereof on a
slightly smaller scale.

The end of the bench not shown in Fig. 2 is
substantially like the end thereof which is shown
in Fig. 2 except for the difference in the number
and position of the legs as is apparent from the
drawing.

I claim:

The ornamental design for a bench for lathes
or the like, as shown and described.

HENRY H. LOGAN.
